UNITED STATES PATENT OFFICE.

JULIUS PEGEL, OF PHILADELPHIA, PENNSYLVANIA, ASSIGNOR TO JOHN BROMLEY & SONS.

DESIGN FOR A RUG.

SPECIFICATION forming part of Design No. 20,369, dated December 9, 1890.

Application filed August 30, 1890. Serial No. 363,562. Term of patent 3½ years.

To all whom it may concern:

Be it known that I, JULIUS PEGEL, a subject of the Emperor of Germany, residing in the city of Philadelphia, State of Pennsylvania, have invented and produced a new and original Design for a Rug, of which the following is a full, clear, and exact description, reference being had to the accompanying drawings, forming a part of this specification.

My invention has relation to the surface ornamentation of a rug; and it consists of the design therefor, as shown in the accompanying photographic drawing, to which reference is made, and which illustrates one-half of the rug, the other half being precisely similar.

The design consists of several segregable parts—namely, the border, (marked A,) which

surrounds a field center, the outline of which is of the form shown at C, and the center piece, as shown at B.

20

I claim—

1. The design for a rug, substantially as shown and set forth.
2. The design for the border A of a rug, substantially as shown and set forth.
3. The design for a center piece for a rug, substantially as shown and set forth.

25

In testimony whereof I have hereunto affixed my signature this 31st day of July, A. D. 1890.

JULIUS PEGEL.
